SIGNAL SYSTEM

William D. Lindsey, South Orange, N. J., assignor,
by mesne assignments, to The Sealand Corporation,
a corporation of Connecticut

Application November 17, 1933, Serial No. 698,389

13 Claims. (Cl. 179—5)

The invention herein disclosed relates to a signal system and in particular to a system in which spoken instructions are given to direct a course of procedure upon the happening of a particular event.

In the event of the existence of a dangerous condition, which might endanger human lives, such, for example, as a fire in an occupied building, an alarm is commonly sounded by the one discovering the condition, or in the case of automatic detection, by the mechanism. The alarm is usually designed to alarm the occupants of the building to the existing danger. Such alarms do in fact alarm people and are conducive to the production of that unreasoning fear which causes a panic and a catastrophe. Frequently, this condition is brought about where there is no imminent danger and could often be avoided by the voice of a person having presence of mind and directing a course of action for the evacuation of the building, and it is the object of this invention to provide a signal system which will not alarm occupants of a building in which a dangerous condition exists but which will provide directions for an orderly evacuation of the building.

By the invention herein disclosed, a signal system is provided in which a sound reproducing system is used to notify the occupants of the building of a dangerous condition and to direct their exit from the building. In accordance with the invention, loudspeakers are mounted in strategic locations throughout the building such that every occupant of the building will be within hearing distance of a loudspeaker. A sound record is interconnected with the system and upon operation of the system directs, through the loudspeakers, the evacuation of the building. In the case of a signal system to be used in the event of a fire, the operation of which is effected either manually or automatically, the sound reproducing system is set into operation upon the automatic or manual initiation of the operation of the system.

In one system which embodies the invention and which is particularly suitable for use in the event of a fire in a school building, includes a plurality of loudspeakers distributed throughout the building, one in each classroom and such other rooms as are occupied by the students. In this system there is provided a control panel on which all of the control units of the system are mounted, an amplifier unit, a sound record and an electrical pick-up. The system may be set into operation either manually or automatically through a thermo-responsive device. In

either event, the electrical pick-up is connected to the amplifier and the amplifier is connected to the several loudspeakers throughout the building. The electrical pick-up translates the sound record into electrical impulses which are amplified and distributed to the loudspeakers where they are translated into sound. When the system is set into operation, in accordance with one sound record, a blare of trumpets is heard from the loudspeakers which attracts the attention of the occupants of the building. This is followed by a siren obligato which rivets the attention of the occupants of the building upon the loudspeakers and then an announcement follows, approximately as follows:

"This is a fire emergency—but there is no danger! You—every one—must leave the building promptly. Close all windows and doors. Leave your hats, coats and books. Take your place in line. You have been drilled; you know just what to do! March out when I give the command 'Go! Don't push! There is no danger! Follow the green arrows to safety! All set—mark time—Left! Left! Left! Left! Go!"

Upon the statement "Mark time" a march is played to which the students march out of the building. Interposed with the music at short intervals, such statements as "Keep in line", "Follow the green arrows", "There is no danger", "Follow the green arrows to safety" are emitted to soothe the excited students and prevent any condition which would cause a panic.

A feature of this system is the fact that it may be used as a public address system. For this purpose there is provided an announcement panel which contains a microphone that may be manually connected into the system. The interconnection of the microphone into the system is, however, made dependent upon the continued inaction of the controls which are set in operation in the event of an actual fire. When the controls set in operation by an actual fire are actuated, the interconnection of the microphone is rendered inoperative for a period of ninety seconds in which the directions for the evacuation of the building are given by the automatic sound reproducing system. Thereafter the superintendent or any other person in charge can cut in on the microphone and direct the further course, that is, a return of the students to their classrooms, or any other course of procedure.

Another feature of the system is the fact that all of the elements thereof are under continuous electrical supervision. This supervision includes,

as well as the various microphones, record operating motors and controls and circuit interconnections, the filaments of the thermionically active tubes of the amplifiers.

5 Another feature of the system is the fact that the filaments of the thermionically active tubes of the amplifiers are preheated so that it takes but a matter of a few seconds to bring the filaments to operating temperatures when the operation of the system is effected.

This sound signal system may be interconnected with local and remote signals for visually directing the evacuation of the building and for calling the fire department.

15 Such a system is disclosed in the accompanying drawings and described in detail below from which illustration and description a clearer understanding of the invention may be had.

In the drawings:

20 Fig. 1 illustrates the control panel of the system;

Fig. 2 illustrates the amplifier unit;

Fig. 3 illustrates the announcing panel; and

25 Fig. 4 is a diagram of the interconnection of this sound signal system with other signal systems.

The system illustrated in the drawings includes a sound record of the phonograph type which is mounted upon a rotatably mounted table that is 30 driven by a motor 1, an electrical pick-up 2 which cooperates with the sound record, an amplifier 3 for amplifying the electrical impulses and a series of loudspeakers 4a, 4b and 4c. The table motor 1 is a 110 volt motor and it is supplied with current by a generator 5 which is driven by a motor 5', the generator producing an alternating current of 60 cycles at 110 volts. The motor generator set is provided in order to render the system independent of any particular external electrical supply. The motor 5' is a thirty-two volt motor and is driven from a battery 6 which is connected to a control panel 7 by line wires A1 and A2 and battery connectors 6a and 6b on the panel.

Normally, the electrical pick-up 2 is connected 45 into a supervisory circuit. This supervisory circuit includes positive line wire A1, a supervisory relay 8, a conductor B1, a stationary contact 9a of a relay 9, a cooperating movable contact 9b normally in contact with the contact 9a, a conductor B2 connecting the contact 9b and one side of the electrical pick-up through a connector 2a on the panel, a conductor B3 connecting the other side of the pick-up through a connector 2b to a movable contact 9c of the relay 9, a stationary contact 9d of the relay 9 and normally engaging the contact 9c and a conductor A3 connecting the connector 9d to the negative line wire A2. The supervisory relay 8 into which the pick-up 2 is normally connected controls two trouble circuits, one which effects the operation of a local or immediate visual trouble signal or light 10 indicating when lighted the specific circuit on which the trouble exists and the other a remote trouble circuit. The immediate trouble circuit includes a conductor A4, which connects the positive line wire and forms in effect a continuation thereof, to which one side of the trouble light 10 is connected, the trouble light 10, a conductor C1 which connects the trouble light to a stationary contact 8a of the relay 8, a cooperating movable contact 8b, a conductor C2 which connects movable contact 8b to a common conductor C3 a conductor C4 connecting the conductor C3 and a stationary contact 11a of a relay 11, a movable contact 11b cooperating with the stationary con-

tact 11a and a conductor C5 which connects the movable contact 11b to the negative line wire A3.

Upon the simultaneous operation of relay 9 and a relay 12, the pick-up 2 is connected to the input side of the amplifier 3. When the relay 9 operates the conductors B2 and B3 connecting the pick-up with the movable contacts 9b and 9c of the relay 9 are connected to conductors B4 and B5 through stationary contacts 9e and 9f respectively of relay 9 which are engaged by the movable contacts 9b and 9c upon energization of relay 9. The conductors B4 and B5 are also respectively connected to stationary contacts 12e and 12f of relay 12 which upon energization of relay 12 are engaged by movable contactors 12b and 12c actuated by relay 12. The contactors 12b and 12c are connected respectively to conductors B6 and B7 which are also connected to connectors 13a and 13b on the panel 7. The connectors 13a and 13b are connected through conductors B8 and B9 to connectors 13'a and 13'b on the amplifier which are the input connectors of the amplifier.

The output of the amplifier is connected 25 through a relay 14 to the loudspeakers. The output connectors 15'a and 15'b of the amplifier are connected by conductors B10 and B11 to connectors 15a and 15b on the panel 7. These latter connectors are connected by conductors B12 and B13 respectively to stationary contacts 14a and 14b on the relay 14. The relay 14 is normally de-energized but upon energization, the contacts 14a and 14b are engaged by movable contacts 14c and 14d respectively. The movable contacts 14c and 14d are connected by conductors B14 and B15 to connectors 16a and 16b to which the three loudspeakers 4a, 4b and 4c are connected in series.

The simultaneous operation of relays 9, 12, 11 and 14 for the purpose of connecting the pick-up through the amplifier to the loudspeakers is effected upon the operation of a relay 17. The relay 17 may be controlled directly by a fire circuit or indirectly through a fire relay. In conjunction with Fig. 1 of the drawings there is illustrated a fire circuit for the purpose of operating the relay 17. This circuit includes a thermo-responsive cable 18 of the type illustrated and described in the copending application of William D. Lindsey, Serial No. 352,624, filed April 5, 1929, for Cable and method of producing the same, and a supervisory relay 19 which acts as a supervisory relay for this fire circuit. The fire circuit includes a conductor A5 which is connected to the positive line wire A1 and to which one side of the relay 17 is connected by a conductor D1, a conductor D2 connecting the other side of the relay 17 and one side of the relay 19, a conductor D3 connecting the relay 19 and a connector 19a on the panel 7, a conductor D4 connecting the connector 19a and one side of an element D5 of the thermo-responsive cable 18, a resistance 20 connecting the other end of the element D5 with the corresponding end of another element D6 of the thermo-responsive cable 18 and a conductor D7 connecting the other end of the element D6 with the negative terminal 6b of the battery. Upon the existence of abnormal thermal conditions, the elements D5 and D6 which are normally insulated become electrically connected. Upon the happening of such an event the resistance 20 is cut out of the circuit D. The resistance 20 is such as to prevent a flow of current through the circuit which is sufficient to operate the relay 17 but to permit a current which is sufficient to maintain 70 75 80 85 90 95 100

the relay 19 energized. Upon the resistance 20 being cut out of the circuit, however, the current flowing through the circuit is increased sufficiently to energize relay 17. The same effect, that is, the shunting of the resistance 20 of the fire circuit, may be accomplished manually through a manual fire box illustrated diagrammatically at 21. This manual fire box is merely a switch which is connected across the terminals of the resistance 20. Upon closing the switch, the resistance 20 is shunted out of the circuit D.

Relay 17 has three pair of cooperating fixed and movable contacts 17a—17b, 17c—17d and 17e—17f. The cooperating movable and fixed contacts 17d and 17c are normally open but become engaged upon the energization of the relay. These two contacts are connected into and control a circuit including the relays 11 and 14 connected in series. This circuit includes a conductor E1 connecting the conductor A3 and the movable contact 17d, fixed contact 17c, a conductor E2 connecting fixed contact 17c and relay 11, a conductor E3 connecting relay 11 and relay 14 and a conductor E4 connecting relay 14 and positive line wire A5. Thus, upon the energization of relay 17, relays 14 and 11 are energized.

Upon being energized, relay 11 actuates the movable contact 11b thereof and it is separated from the contact 11a and engages a stationary contact 11c. Engagement of the contacts 11b and 11c effects the energization of the relays 9 and 12. These two relays are connected in series with five other relays 22, 23, 24, 25 and 26 which are energized simultaneously with relays 9 and 12. The circuit completed by the contacts 11a and 11b and effecting the energization of these several relays includes negative line wire A3, conductor C5, movable contact 11b of relay 11, fixed contact 11c, conductor F1 connecting contact 11c and one side of relay 22, relay 22, a conductor F2 connecting relay 22 and relay 23, relay 23, a conductor F3 connecting relay 23 and relay 24, relay 24, a conductor F4 connecting relay 24 and relay 25, relay 25, a conductor F5 connecting relays 25 and 26, relay 26, a conductor F6 connecting relay 26 and relay 9, relay 9, a conductor F7 connecting relays 9 and 12, relay 12, a conductor F8 connecting the relay 12 and a connector 27, conductor F9 connecting the connector 27 and a movable contact 28a of a relay 28, a fixed contact 28b of relay 28 which engages contact 28a when relay 28 is energized, and a conductor F10 to which contact 28b is connected and which is also connected to the positive line wire A1. It will be apparent of course that the completion of the circuit including these several relays connected in series and consequently the simultaneous operation thereof is dependent upon the operation of the relay 28. This relay is, however, connected in series with a relay 29 and the two relays connected across the battery upon the operation of the relay 11. The relay 29 is therefore energized and the circuit including the several relays and the battery is completed upon the operation of relay 11.

The circuit for energizing the relay 28 upon the operation of the relay 11 includes negative conductor A3, conductor C5 connecting the negative conductor A3 and the movable contact 11b of relay 11, fixed contact 11c, conductor F1, a conductor G1 connecting conductor F1 and the movable contact 30f of a relay 30. The movable contact 30f normally engages a fixed contact 30g of the relay 30 and the fixed contact 30g is connected by a conductor G2 to one side of the relay 29. The other side of the relay 29 is connected by a

conductor G3 to one side of relay 28 and the other side of relay 28 is connected to the positive conductor F10. Thus the relays 28 and 29 are connected in series by the energization of the relay 11 and these two relays are operated simultaneously with the operation of relay 11.

Through the circuits and the operation of the relays as above described the electrical pick-up is connected through the amplifier to the loud-speakers 4a, 4b and 4c. At the same time, the operation of the relays 28 and 29 effects the operation of the turntable motor 1 which drives the table on which the phonograph record is mounted. This turntable and the cooperating electrical pick-up are well known commercial instruments and are not therefore illustrated and described in detail. The phonograph, that is, the electrical pick-up and the record, are reset automatically when the electrical pick-up has completely traversed the record. Upon the energization of the relay 28, the motor 5' which drives the generator 5 is connected across the battery and the generator is connected to 110 volt line wires which supply the motor 1 and the filaments of the thermionically active tubes of the amplifier. The relay 28 has movable contacts 28a, 28b and 28c. Cooperating with the movable contact 28a there is a fixed contact 28d which is normally separated from the contact 28a. Cooperating with the contact 28b there are two fixed contacts 28e and 28f. The contact 28b normally engages the contact 28e and is normally separated from the contact 28f. The contact 28c also has two fixed contacts 28g and 28h with which it cooperates. Normally the contact 28c engages the contact 28h and is separated from the contact 28g. Upon energization of the relay contact 28a engages contact 28d and the circuit to the motor is closed which circuit includes a conductor H1 which connects one side of the motor with the conductor F10, a conductor H2 connecting the other side of the motor with the movable contact 28a and a negative conductor H3 which is connected to the contact 28d and to the negative line wire A2 through a connector on the panel 7. The motor 5' is thus connected across the battery and is operated. The contact 28b is connected through a relay 28' to one side of the generator 5 by conductors I1 and I2, the conductor I1 connecting the contact 28b and one side of the relay, and the conductor I2 connecting the other side of the relay and the generator. The other side of the generator is connected by a conductor I3 to the contact 28c and by a branch conductor i to the stationary contact 28f. The contact 28g cooperating with the contact 28b and engaged thereby when the relay 28 is operated is connected by a conductor I4 to a 110 volt line wire J1. Thus when the relay 28 is operated, the relay 28' is connected across the generator and the conductor I3 is connected to the conductor I4 and thus to the 110 volt line wire J1. This connection is through the engagement of the movable and fixed contacts 28b and 28f and the movable and fixed contacts 28c and 28g. The engagement of the contacts 28b and 28f place the relay 28' across the generator and the engagement of the contacts 28c and 28g connect the conductors I3 and I4. The relay 28' which is a potential relay has three movable contacts 28'a, 28'b and 28'c. Upon energization contact 28'a is brought into engagement with a stationary contact 28'd. Contact 28'a is connected to the conductor I2 and thus directly to one side of the generator. The contact 28'd

is connected by a conductor I5 to a 110 volt line wire J2. On engagement of the contacts 28'a and 28'd of the relay 28, therefore, the line wire J2 is directly connected to one side of the generator, the line wire J1 being directly connected to the other side of the generator as heretofore explained. Contact 28'c cooperates with a stationary contact 28'g and engages this stationary contact upon energization of the relay 28'. The contact 28'c is connected to the conductor I1 and its cooperating contact 28'g is connected by a branch conductor I2 to the conductor I3. With these interconnections it will be observed that the engagement of the contacts 28'c and 28'g connects the relay 28' across the generator independently of the contacts 28b and 28f of the relay 28. In this way the motor generator set is operated and the generator is connected to the 110 volt line wires J1 and J2. These line wires are connected at one end respectively to fixed contacts 29c and 29d of relay 29. These two contacts are engaged by movable contacts 29b and 29d upon the energization of the relay 29. The movable contacts 29b and 29d are connected respectively through conductors K1 and K2 to the table motor. Consequently upon the energization of relays 28 and 29 the generator and the table motor I are directly connected and the motor is operated. With the operation of the table motor I the recorded sound is transposed into electrical impulses by the electrical pick-up which impulses are delivered to the amplifiers wherein they are amplified and as amplified sent through to the loudspeakers of the system.

The amplifier is an ordinary commercial amplifier with the exception of the character of the connection of the secondary of the transformer to the ground and the connection to the filaments of the tubes. Taps from the secondary of the transformer are connected to conductors K'1 and K'2. The conductors K'1 and K'2 are connected respectively to fixed contacts 28'e and 28'f of the relay 28'. These two fixed contacts are engaged by the movable contact 28'b when the relay 28' is energized. The movable contact 28'b is connected by a conductor K'3 to the ground connection of the amplifier. Thus upon the operation of the relay 28' the taps on the secondary of the transformer are connected to the ground and when the relay 28' is deenergized they are not connected to the ground.

During all times that the system is inoperative, the filaments of the tubes of the amplifier are connected into a closed electrical supervisory circuit L so that there is constant electrical supervision of these tubes. The current flowing through the circuit is insufficient to raise the filaments to operating temperatures but it is sufficient to effect a preheating of the tubes so that upon the operation of the system and the reconnecting of the tubes, it takes less time than normally for the tubes to reach operating temperatures. The normal supervisory circuit including the filaments of the tubes is as follows: conductor A5 which connects the positive line wire A1 and a fixed contact 22a of relay 22, movable contact 22b of relay 22 which normally engages contact 22a, a conductor L1 connecting the movable contact 22b and a connector 31 on the panel 7, a conductor L2 connecting the connector 31 and a connector 31' on the amplifier, a conductor L3 connecting connector 31' and one side of a filament 32a of a thermionically active tube 32 in the amplifier, a conductor L4 connecting the other side of the filament 32a with a connector 33' on

the amplifier, a conductor L5 connecting the connector 33' and a connector 33 on the panel 7, a conductor L6 connecting the connector 33 and movable contact 22d of relay 22, a fixed contact 22e of relay 22 normally engaging contact 22d, a conductor L7 connecting fixed contact 22e of relay 22 and a fixed contact 23a of relay 23, a movable contact 23b of relay 23 which normally engages fixed contact 23a, a conductor L8 connecting the movable contact 23b and a connector 34 on the panel 7, a conductor L9 connecting contactor 34 and a connector 34' on the panel and the amplifier respectively, a conductor L10 connecting connector 34' and one side of a filament 35a of a thermionically active tube 35, a conductor L11 connecting the other side of the filament 35a and a connector 36' on the amplifier, a conductor L12 connecting the connector 36' on the amplifier with a connector 36 on the panel 7, a conductor L13 connecting the connector 36 and a movable contact 23e of relay 23, a stationary contact 23f of relay 23 which normally engages contact 23e, a conductor L14 connecting the stationary contact 23f of relay 23 with a stationary contact 24a of relay 24, a movable contact 24b of relay 24 which normally engages contact 24a, a conductor L15 connecting the contact 24a and a connector 37 on the panel 7, a conductor L16 connecting connector 37 on the panel 8 with a connector 37' on the amplifier, a conductor L17 connecting connector 37' and one side of a filament 38a of a thermionically active tube 38, a conductor L18 connecting the other side of the filament 38a with a connector 39' on the amplifier, a conductor L19 connecting the connector 39' on the amplifier with a connector 39 on the panel 7, a conductor L20 connecting the connector 39 with a movable contact 24e on the relay 24, a stationary contact 24f of relay 24 which normally engages contact 24e, a conductor L21 connecting contact 24f and a contact 25a of relay 25, a movable contact 25b of relay 25 which normally engages the contact 25a, a conductor L22 connecting the movable contact 25b to a connector 40 on the panel, a conductor L23 connecting the connector 40 with a connector 40' on the amplifier, a conductor L24 connecting the connector 40' with one side of a filament 41a of a thermionically active tube 41, a conductor L25 connecting the other side of the filament of the tube 41 with a connector 42' on the amplifier, a conductor L26 connecting the connector 42' of the amplifier with a connector 42 on the panel 7, a conductor L27 connecting the connector 42 with a movable contact 25e of the relay 25 which engages the contact 25e, a conductor L28 connecting stationary contact 25f with a stationary contact 26a of relay 26, a movable contact 26b of relay 26 which normally engages contact 26a, a conductor L29 connecting the movable contact 26a and a connector 43 on the panel 7, a conductor L30 connecting the connector 43 on the panel 7 with the connector 43' on the amplifier, a conductor L31 connecting the connector 43' and one side of a filament 44a of a thermionically active tube 44, a conductor L32 connecting the other side of the filament 44a with a connector 45' on the amplifier, a conductor L33 connecting the connector 45' with a connector 45 on the panel 7, a conductor L34 connecting the connector 45 and a movable contact 26e of the relay 26, a fixed contact 26f of relay 26 which normally engages movable contact 26e, a conductor L35 connecting fixed contact 26f and a negative con-

ductor A6 which is connected to negative line wire A2. The connection between the contact 26f and the negative conductor A6 is through a resistance 46 which controls the current flowing through this series circuit including the filaments of the several vacuum tubes of the amplifier. Upon the simultaneous operation of the relays 22, 23, 24, 25 and 26, as heretofore described, this series connection of the filaments of the vacuum tubes and the battery 6 is changed so that the filaments of the tubes are connected in parallel across the secondary of a transformer 48 which is supplied by the generator 5, with an alternating current at 110 volts and 60 cycles. This parallel connection to the transformer provides a sufficient voltage and current for raising the temperature of the tubes to operating temperature. However, due to the preheating of the filaments by the supervisory current, the filaments are raised to operating temperature in a period of approximately eight seconds.

Upon the operation of relays 22, 23, 24, 25 and 26, the movable contacts b and d of these relays are disengaged from the contacts a and e and are brought into engagement with contacts c and f. The connection of the contacts b and d of any one of these relays with the contacts c and f connects one of the tubes in parallel with the transformer 48 in the amplifier. Upon the operation of the relay 22, the filament 32a of the tube 32 is connected to the transformer. The circuit through which this connection is accomplished includes conductors L3 and L4, connectors 31 and 33' on the amplifier, conductors L2 and L5, connectors 31 and 33 on the panel 7, conductors L1 and L6, movable contacts 22b and 22d, fixed contacts 22c and 22f of relay 22, conductors M1 and M2 connecting respectively the contacts 22c and 22f of relay 22 with connectors 48a and 48b on the panel 7, conductors M3 and M4 connecting the connectors 48a and 48b on the panel 7 with connectors 48'a and 48'b on the amplifier, and conductors M5 and M6 connecting the connectors 48'a and 48'b to the opposite sides of a coil 47a of the transformer 47. Similar circuits connect the filaments of the tubes 35, 38, 41 and 44 to coils 47b, 47c, 47d, 47e and 47f respectively of the transformer 47 upon the operation respectively of relays 23, 24, 25 and 26. These circuits include the several conductors M7 to M30 arranged as the conductors M1 to M6 inclusive of the circuit to the tube 32. Upon the operation of relay 17 therefore relays 9, 11, 12, 14, 22, 23, 24, 25, 26, 28 and 29 are operated and effect the operation of the system to reproduce in the loudspeakers the sound which has been recorded on the phonograph record that is carried by the table driven by the motor 1. When this operation is effected, directions and music as heretofore described are emitted from the loudspeakers.

As heretofore stated, the relay 28' is a potential relay and it is deenergized upon a slight reduction in the voltage of the generator. The arrangement of this relay is such that the relay operates to cut the generator off from the amplifier before the filaments of the tubes are cooled by virtue of the deenergization of relays 23, 24, 25 and 26 which connect the filaments of the tube into operative relation with the generator.

The system may also be operated as a public address system for ordinary purposes such as making ordinary announcements and also in the event that after the system is automatically operated in response to abnormal thermal condi-

tions, the fire producing the abnormal thermal conditions is discovered and extinguished and it becomes desirable to halt the evacuation of the building. For this purpose, there is provided an announcing panel 49 which carries a microphone 50 and a switch 51 which when closed effects the interconnection of the microphone into the system. The panel board 49 is commonly located in the principal's office and in addition to the microphone carries trouble signals that indicate trouble in the system. The microphone is connected into the system through a circuit N which includes a conductor N1 which connects a connector 52a on the panel 7 to the positive line wire A1, a conductor N2 which connects the connector 52a to one side of a choke coil 53, a conductor N3 which connects the other side of the choke coil to a connector 52b on the panel 7 and a conductor N4 which connects the connector 52b to a connector 54a also mounted on the panel 7. The conductor N4 is also connected to the negative line wire A2 through a condenser 55. A conductor N5 extends between the panels 7 and 49 and connects the connector 54a on the panel 7 to a connector 54'a on the panel 49. The connector 54'a is connected by a conductor N6 to one side of the microphone, the other side of which is connected through a conductor N7 to another connector 54'b adjacent the connector 54'a. This latter connector is connected through a conductor N8 to a connector 54b on the panel 7 and through the connector 54b and a conductor N9 to a connector 55a on the panel 7. The connector 55a is connected to a conductor N10 which connects the connector to one side of the primary of a microphone transformer 56. The other side of the primary of the microphone transformer is connected through a conductor N11, a connector 55b and a conductor N12 to a stationary contact 11d on the relay 11. The stationary contact 11d of the relay 11 cooperates with a movable contact 11e which engages the fixed contact 11d upon the energization of the relay 11 but which is normally separated from the contact 11d. The movable contact 11e is connected through a conductor N13 to the negative conductor A3. Thus when the relay 5 is energized and the contacts 11d and 11e are closed there is a complete circuit through the microphone and the microphone transformer 56.

The secondary of the microphone transformer 56 is normally connected to the terminals 13a and 13b which, as heretofore described are connected to the input side of the amplifier 3. This connection includes conductors N14 and N15 which connect the secondary of the transformer to connectors 57a and 57b respectively. The connectors 57a and 57b are connected through conductors N16 and N17 to fixed contacts 12a and 12d respectively of the relay 12. The contacts 12a and 12d normally engage the movable contacts 12b and 12c of the relay 12 which, as heretofore described, are connected respectively through the conductors B6 and B7 to the connectors 13b and 13a and thus to the input side of the amplifier 3.

The connection of the microphone into the system is, as heretofore stated, dependent upon the energization of relay 11. When it is desired to use the system as a public address system, relay 11 may be energized through the action of the relay 30. The relay 30 includes a contact 30d which is connected by a conductor O1 to the conductor E2. The contact 30d cooperates with a movable contact 30c which is connected by a

conductor O2 to the negative conductor A3. The contacts 30c and 30d are normally separated but are brought together upon the energization of relay 30. Upon the connection of these contacts, a circuit is completed through relays 11 and 14, the circuit including the negative conductor A3, the conductor O2, contacts 30c and 30d, conductor O1, conductor E2, relay 11, conductor E3, relay 14, conductor E4 and the negative conductor A5. The energization of relay 30 also effects the operation of relays 22 to 26 inclusive so as to properly connect the vacuum tubes of the amplifier unit into operative relation and the energization of this relay also effects the operation of relay 28 to cause the operation of the motor generator set and thus provide the current at the necessary voltage for the operation of the amplifier unit. The operation of relays 9 and 12 is, however, prevented upon the operation of the relay 30 and thus the microphone circuit is maintained connected to the input side of the amplifier.

The operation of relays 22 to 26 and the shunting of the relays 9 and 12 so as to prevent their operation is accomplished through contacts 30a and 30b of the relay 30. Contact 30b is connected through a conductor P1 to the conductor F6 which, as heretofore described, is connected to one side of the relay 9. Thus upon the operation of the relay 30 and the energization of relay 11, as heretofore described, a circuit is completed through the relays 22 to 26 inclusive as follows: negative conductor A3, conductor C5, contact 11b of relay 11, contact 11c which is engaged by contact 11b upon the operation of the relay 11, conductor F1, relays 22 to 26 in series, conductor F6, a conductor P1, fixed contact 30b of relay 30, movable contact 30a of relay 30, a conductor P2 connecting movable contact 30a and conductor F8, conductor F8, movable contact 28a of relay 28, fixed contact 28b of relay 28 which is engaged by contact 28a upon the energization of relay 28 and positive conductor F10. In this manner the relays 22 to 26 are operated, the explained operation assuming the operation of relay 28 the operation of which will be explained. The relays 9 and 12 are however shunted out of the circuit through the closing of the contacts 30a and 30b of relay 30. This shunt circuit includes contact 30b, conductor P1, conductor F6, relay 9, conductor F7, relay 12, conductor F8, conductor P2, and movable contact 30a of relay 30. Thus, upon the operation of the relay 29 the relays 9 and 12 remain deenergized.

The operation of the relay 28 is effected upon the movement of contact 30f into engagement with a contact 30e of the relay 30. Upon the energization of the relay 29 contact 30f separates from contact 30g and engages the contact 30e. Contact 30e is connected through a conductor Q1 to one side of the relay 28. The other side of the relay 28 is, as heretofore described, connected to the positive conductor F10. The movable contact 30f is connected, as heretofore described, through the conductors G1 and F1 to the fixed contact 11c of the relay 11 which engages the contact 11b and is thus connected to the negative conductor A3. The circuit through relay 28 which causes the energization thereof therefore includes positive conductor F10, relay 28, conductor Q1, contacts 30e and 30f of relay 30, conductors G1 and F1, contacts 11c and 11b of relay 11, and conductors C5 and A3. The effect

of the energization of relay 28 is as heretofore described, viz., this relay effects the operation of the motor generator set and the connection of that set to the amplifier. Relay 29 is not operated upon the energization of relay 30 and the phonograph portion of the system remains dormant and does not interfere with the operation of the system through the microphone. It will thus be apparent that upon the operation of relay 30 the system is connected to operate through the microphone as a public address system.

The relay 30 is, as heretofore described, energized upon the closing of the single pole switch 51 on the announcing panel 49. The circuit R 15 which includes the relay 30 includes the positive conductor A1, a conductor R1 which connects the positive conductor to a supervisory relay 58, a conductor R2 connecting the supervisory relay and the relay 30, a conductor R3 connecting the relay 30 and which is connected in common to the stationary contact 17a of relay 17 and the stationary contact 59a of a relay 59. Normally, when the relay 17 is not operated the contact 17a is in contact with a movable contact 17b which is connected through a conductor R4 to a connector 60 on the panel 7. A movable contact 59b of the relay 59, which is normally separated from the contact 59a but which engages the contact 59a upon energization of the relay 59, is also connected to the conductor R4 and thus to the connector 60. The connector 60 is connected through a conductor R5 to a connector 60' on the announcing panel and through the connector 60' to one side of the switch 51 by a conductor R6. The other side of the switch 51 is connected by a conductor R7 to the negative battery connector 61a on the panel 49. This connector is connected to the negative side of the thirty-two volt battery 6. Across the normally open switch there is connected a resistance 62. This resistance closes the circuit R just described. The resistance is such that the current flowing through the circuit is insufficient to operate the relay 30 but it is sufficient to operate the supervisory relay 58. Upon closing the switch 51, the resistance 62 which is connected across the switch will be shunted out of the circuit and upon the happening of that event, sufficient current flows through the circuit to operate the relay 29. The switch 51 is located just below the microphone and is manually operated. Preferably, it is a switch that when released, automatically opens.

It is to be noted that the circuit to the relay 30 is through fixed and movable contacts 17a and 17b of relay 17. Assuming the inactivity of relay 59, the operation of relay 30 is dependent upon the continued inoperation of relay 17. The fire circuit which operates the relay 17 is therefore given preference over the switch 51 in the control of the system. This preferential operation of relay 17 is modified by the relay 59 so that in the event of the operation of relay 17, its control over the relay 30 is limited to a period of ninety seconds which is sufficient to complete the automatic operation of the system for directing the evacuation of the building, i. e. one complete cycle of operation of the sound record. This is accomplished through relay 59 which is a time relay. Upon the operation of relay 17 contacts 17e and 17f thereof are brought into engagement. Contact 17f is connected by a conductor S1 to the negative conductor A3. Contact 75

17e is connected by a conductor S2 to a heating element 63 associated with the relay 59 and also to one side of the relay 59. The other side of the relay 59 is connected by a conductor S3 in common to a fixed contact 59c of the relay 59 and a fixed contact 63b associated with the element 63. The element 63 is connected through a conductor S4 to a fixed contact 59e of the relay 59 which normally engages a movable contact 59d. The movable contact 59d is connected by a conductor S5 to the positive conductor A5. Upon the operation of relay 17 there is a circuit through the heat element 63 closed which includes the conductor S1, contacts 17e and 17f of relay 17, conductor S2, element 63, conductor S4, contacts 59e and 59d, and conductor S5. The element 63 upon heating brings a movable contact 63a which is associated therewith into engagement with contact 63b. The contact 63a is connected through a conductor S6 to the positive conductor A5. Thus upon the contacting of contacts 63a and 63b which are controlled by the heat element 63, a circuit is completed through the relay 59. This circuit includes the conductor S1, contacts 17f and 17e of relay 17, conductor S2, relay 59, conductor S3, contacts 63a and 63b and conductor S6 to positive conductor A5. Upon energization of relay 59 the relay becomes independent of the heat element 63, the circuit through the relay being completed through contacts 59a and 59d. The operation of relay 59 effects the closing of contacts 59a and 59b and through them the completion of the connection to relay 30 which was broken by the separation of contacts 11a and 17b upon the energization of relay 17. In this way the control of the system by the relay 30 is rendered ineffective for a period of ninety seconds after the operation of relay 17.

From the above description of the operation of the several parts of the system, the operation of the system as a whole will be apparent. In effect the system forms the combination of a public address system and a signal system for audibly directing the evacuation of a building in the event of the existence of a fire. This automatic direction of the evacuation of the building is accomplished through a sound record on which the directions for evacuation have been previously recorded. In practice, it has been found that for a school system the record preferably contains audible signals as described above.

In the system illustrated all of the parts thereof are under constant electrical supervision. In the event of a failure of any part of the system both an audible and a visual signal are automatically given. Since the panel 7 may be located in some obscure part of the building and the panel 49 is located in the principal's office a general signal is given on the panel 49 upon the impairment of the effectiveness of any part of the system. A specific signal indicating the particular circuit in which the trouble exists occurs upon the panel 7.

The fire circuit includes the supervisory relay 19. This relay has two pairs of cooperating fixed and movable contacts 19a-19b and 19c-19d. As heretofore explained, this relay is normally energized, being connected into the closed fire circuit D through which sufficient current flows to energize the relay. Upon a break in this circuit, the relay 19 becomes deenergized and the normally open cooperating contacts become closed, that is, contact 19a engages contact 19b and contact 19c engages contact 19d. Contact 19a is connected by a conductor T1 to one side

of a trouble signal lamp 64 the other side of which is connected to the positive conductor A4. Contact 19b is connected to conductor C3 and thus through conductor C4, contacts 11a and 11b of relay 11 and conductor C5 to the negative conductor A3. Upon the closing of the contacts 19a and 19b, therefore, a circuit is completed through the trouble light 64 which indicates trouble in the fire circuit D. Movable contact 19d of relay 19 is connected to a conductor T2 which is connected to a conductor T3 which connects the conductor T2 and a fixed contact 11f of the relay 11. The fixed contact 11f is normally in engagement with movable contact 11e which, as heretofore described, is connected through the conductor N13 to the negative conductor A3. Upon the de-energization of relay 19, contact 19c is thus connected to the negative side of the battery. Contact 19c is connected through a conductor T4 to a connector 65. Connector 65 is connected through a conductor T5 to a connector 65' on the panel 49. Connector 65' is connected to a relay 66 on the panel 9 which is connected through a conductor T7 in series with a supervisory relay 67, the supervisory relay being also connected through a conductor T8 to the positive battery connector 61b on the panel 49. It will therefore be apparent that upon the operation of relay 19 and the connecting of the contact 19c to the negative side of the battery, a circuit is completed through relays 66 and 67 on the panel 49. Normally, a circuit including relays 66 and 67 is completed through a resistance 68 on the panel 7. The resistance 68 is connected at one side to negative conductor A6 and at the other side to conductor T4. Thus there is at all times a closed circuit including relays 66 and 67. The resistance 68 however, is such that the current flowing through the circuit is insufficient to operate relays 66 but sufficient to operate relays 67. Relay 67 acts as a supervisory relay for the connection between the panel 7 and the panel 49 through which trouble signals are transmitted to the panel 49. Upon the operation of the relay 19 and the engagement of the contacts 19d and 19c, however, resistance 68 is cut out of this circuit and relay 66 is operated.

Upon the operation of relay 66, two pairs of cooperating movable and fixed contacts 66a-66b and 66c-66d become engaged. The engagement of these contacts effects the operation of a specific trouble signal 69 indicating that trouble exists on the sound control panel, and a general audible trouble signal or bell 70. The circuit for the operation of the general audible signal includes the conductor T8 which is connected to the positive connector 61b, a conductor U1 connecting the conductor T8 and one side of the audible trouble signal 70, a conductor U2 connecting the audible trouble signal and the fixed contact 66d of relay 66, movable contact 66c of relay 66, a conductor U3 connecting the movable contact 66c and conductor R7 which is connected to the negative connector 61a. The specific trouble signal or light 69 is connected through a conductor V1 to the conductor U1, and through a conductor V2 to the fixed contact 66b. Movable contact 66a which cooperates with the contact 66b is connected directly to the conductor U3 and thus to the negative battery connector. Thus, upon operation of relay 66 the trouble signals 69 and 70 are operated.

If the trouble circuit connected between the two panels is open, relay 67 becomes deenergized.

Upon deenergization, cooperating fixed and movable contacts 67a—67b and 67c—67d become engaged and effect the operation of the audible general trouble signal 70 and a specific visual trouble signal 71 which indicates when operated trouble in the interconnection between the microphone panel and the control unit for the sound system which interconnection transmits the trouble signal current. The operation of the trouble signal 70 is effected through the contacts 66c and 66d which are respectively connected to conductors U2 and U3. Thus upon engagement of these contacts a circuit is completed to the trouble bell 70. The trouble signal 71, which is a lamp, is lighted upon the engagement of contacts 67a and 67b. The engagement of these contacts completes a circuit which includes conductors T8, U1, V1 to which the lamp 71 is connected, a conductor W connecting the lamp 71 and the contact 67a, contact 67b, conductor U3 to which contact 67b is connected and thus negative connector 67a. With the exception of the signal indicating trouble on the interconnection between the panels which interconnection transmits the trouble signals, the signals on the microphone panel 49 are general in their indication, specific trouble being indicated by trouble lights on the panel 7.

The relay 58 is the supervisory relay for the control circuit R. This relay, like the relay 49, is normally energized and includes two sets of normally separated cooperating fixed and movable contacts 58a—58b and 58d—58c. Contacts 58a and 58b control a circuit to a visual trouble signal 72 on the panel 7. The operation of this light 72 indicates trouble on the control circuit R. Its operation is effected through the connection of contacts 58a and 58b. Contact 58b is connected to conductor C3 and thus normally to the negative conductor A3. Contact 58a is connected through a conductor X to the lamp 72 which is also connected to the conductor A4. Contact 58c of relay 58 is connected to conductor T4 in common with contact 19c. Contact 58d is connected in common with contact 19d of relay 19 to conductor T2. Thus, upon closing of contacts 58c and 58d the resistance 68 is cut out of the circuit T.

The loudspeakers are electrically supervised and normally connected into a supervisory circuit including a supervisory relay 73. This supervisory circuit includes relays 11 and 14 and is as follows: positive conductor A5, conductor E4, relay 14, conductor E3, relay 11, conductor E2, a conductor Y1 connecting conductor E2 and a stationary contact 14e which normally engages the movable contact 14c, conductor B14, loudspeakers 4c, 4b and 4a, conductor B13, contact 14d of relay 14, a fixed contact 14f of relay 14 which normally engages contact 14d, a conductor Y2 connecting contact 14f and relay 13 and a conductor Y3 connecting relay 13 and the negative conductor A6. The current flowing through this closed circuit is sufficient to energize the relay 13 and maintain the contacts thereof normally separated. The relay contains two pairs of fixed and movable contacts 73a—73b and 73c—73d. The contacts 73a and 73b are connected into a circuit including a visual trouble lamp 74. The trouble lamp is connected to the positive conductor A4 and through a conductor Z to the contact 73a of the relay 73. The movable contact 73b is connected to the conductor C3 and thus to the negative side of the battery. Upon engagement of contacts

73a and 73b, that is, upon opening the circuit including the loudspeakers and the relay 73, the light 74 is lighted to give a visual signal indicating trouble in the loudspeaker circuit. Contacts 73d and 73c are respectively connected to the conductors T4 and T2 and when engaged shunt the resistance 68 and effect the operation of the circuit T.

The microphone circuit is also supervised. It is included in a closed circuit which includes a supervisory relay 75. This circuit includes the conductor N1 which is connected to the positive conductor A4, conductor N2, choke coil 53, conductor N3, conductor N4, conductor N5, conductor N6, microphone 50, conductor N7, conductor N8, conductor N9, conductor N10, primary of microphone transformer 56, conductor N11, conductor N12, relay 75 which is connected to conductor N12 and negative conductor A6 to which relay 75 is also connected. Thus there is a closed circuit through the choke coil 53, the microphone 50 and the primary of the microphone transformer 56, relay 75 and the battery 6. Upon the opening of this circuit due to trouble in the microphone the choke coil or the transformer 56, the relay 75 becomes deenergized. Upon deenergization two pairs of fixed and movable cooperating contacts 75a—75b and 75c—75d become engaged. The contacts 75a and 75b connect one side of a visual signal 76 to the conductor C3 and thus to the negative side of the battery. This connection is effected through contact 75b which is connected to conductor C3, contact 75a and a conductor AA which connects contact 75a and the light 76. The light 76 is also connected to conductor A4 which is connected to the light 76. Contacts 75c and 75d shunt the relay 68 out of the circuit T. Contact 75d is connected to conductor T2 and contact 75c is connected to conductor T4. Thus upon engagement, conductors T2 and T4 are connected together, shunting the resistance 68 out of the circuit T.

The supervisory circuit for the electrical pick-up 2 has been described above. The supervisory relay of this circuit includes contacts 8a and 8b which upon deenergization of the relay connect one side of the light 10 to the conductor C3 and thus to the negative side of the battery, the other side of the light 10 being directly connected to the conductor A4. Relay 8 also has a pair of fixed and movable contacts 8c—8d which are connected respectively to conductors T4 and T2 and thus serve upon deenergization of relay 8 to shunt relay 68 out of the circuit T and effect the operation of relay 66 on the microphone panel 49.

The motor and generator of the motor generator set and the relay 28' are connected in series for the purpose of supervision. This series circuit includes the positive conductor H1, the motor 5', the conductor H2, fixed contact 28e of relay 28, movable contact 28b of relay 28, conductor H1, relay 28', conductor I2, generator 5, conductor I3, movable contact 28c, fixed contact 28h normally engaging contact 28c, and a conductor AB connecting contact 28h of relay 28 and one side of a relay 17, the other side of which is connected to the negative conductor A6. If for any reason such as an open in the motor or generator, this circuit is opened, two pairs of cooperating fixed and movable contacts 77a—77b and 77c—77d are brought into engagement. The engagement of contacts 77a and 77b effect the illumination of a trouble light 78, which indicates that there is trouble in the motor generator circuit. One side

of the light 78 is connected in common with the other trouble lights to the positive conductor A4. The other side of the light is connected through a conductor AC1 to the contact 77a. Contact 77b is connected through a conductor AC2 to a movable contact 29g of relay 29. Contact 29g normally engages the fixed contact 29h of the relay 29 which is connected by a conductor AC3 to the negative conductor H3. Contacts 77c and 77d are respectively connected to conductors T2 and T4 in common with several corresponding contacts of the other supervisory relays.

The motor 1 for rotating the table of the phonograph is likewise supervised. The closed supervisory circuit for this motor includes the positive conductor F10, normally closed contacts 29a and 29b of relay 29, conductor K1, motor 1, conductor K2, contact 29e of relay 29 which normally engages contact 29f of relay 29, a conductor AD which connects the connector 29h and a supervisory relay 79, which is also connected to the negative conductor A6. Supervisory relay 79 includes fixed and movable contacts 79a-79b and 79c-79d. Contacts 79a and 79b control the operation of a trouble light 80. The light 80 is connected to the positive conductor A4 and through a conductor AE to the contact 79a. Contact 79b is directly connected to conductor C3 and thus normally to the negative side of the battery. Contacts 79c and 79d are respectively connected to conductors T4 and T2.

The filaments of the thermionic tubes of the amplifier are also connected into a supervisory circuit. As heretofore described, the filaments of these tubes are normally connected in a series circuit L. To the conductor L35 of this series circuit, a conductor AF connects one side of a supervisory relay 81. The connection to the supervisory relay is through a resistance 82. The relay 81 is also connected to the conductor A6. In this circuit there is a division of current between the conductor AF and the conductor L35 which is connected through the resistance 46 to the conductor A6. The division of current is such that there is sufficient current flowing through the series-connected tube elements to preheat these elements and a lesser current flowing through the relay 81. It is to be noted however that the energization of relay 81 is dependent upon the continuance of the closed circuit L. Upon the opening of the circuit L the relay 81 becomes deenergized and closes two pair of normally fixed and movable contacts, 81a-81b and 81c-81d. The deenergization of this relay is indicated by a trouble light 83 one side of which is connected to the positive conductor A4 and the other side of which is connected to the contact 81a of relay 81. Cooperating contact 81b is connected in common with the contact 77a of relay 77 to the conductor AC2 which, as heretofore described, is connected through contacts 29g and 29h of relay 29 to the negative conductor H3. The completion of this circuit therefore by the engagement of contacts 81a and 81b effects the operation of the visual signal 83 indicating trouble with the filament circuit L. Contacts 81c and 81d are respectively connected to conductors T4 and T2 and thus upon energization effect the operation of the remote signals 69 and 70 on the microphone panel 49.

Relays 9, 12, 22 to 26 inclusive, 28 and 29 are vital for a fire or emergency announcement. Because of this, the windings of these several relays are normally connected in series and are included in a closed supervisory circuit so that the relays are under constant electrical supervision. The trouble light for this circuit is indicated at 84 and the supervisory relay at 85. The circuit is as follows: positive conductor F10, relay 28, conductor G3, relay 29, conductor G2, contacts 30g and 30f of relay 30, conductor G1, relay 22, conductor F2, relay 23, conductor F3, relay 24, conductor F4, relay 25, conductor F5, relay 26, conductor F6, relay 9, conductor F7, relay 12, conductor F8, a conductor AF connecting conductor F8 to movable contact 28a and one side of relay 85, and negative conductor A6 which is connected to the other side of relay 85. Upon the opening of this circuit either through injury to any of the relays or the interconnection between the relays, supervisory relay 85 which is normally energized by the current flowing through the circuit becomes deenergized. This relay includes two sets of fixed and movable contacts 85a-85b and 85c-85d. The contact 85a is connected to one side of the light 84 by a conductor AG. The other side of the light 84 is connected to the positive conductor A4. Contact 85b is connected to conductor C3 and thus normally to the negative side of the battery. Upon the engagement of contact 85a and 85b therefore the light 84 is illuminated indicating trouble in this relay circuit. Contacts 85c and 85d are respectively connected to the conductors T4 and T2 so that when these contacts become engaged upon the deenergization of the relay 85 the resistance 68 is cut out of the circuit 30 T and the remote trouble signals are operated.

The operation of relay 85 is also effected when the phonograph portion of the system is partially operated. If for any reason this portion of the system is not set to commence operating and give the directions for evacuating the building upon the operation of the fire circuit, the relay 85 is deenergized and the signal 84 together with the remote signals are operated. Upon the operation of the table motor 1 and until the pick-up 40 has completed a cycle and is reset in the position to start the operation of another cycle, a switch 86 is maintained open. This switch is only closed when the several parts of the phonograph portion of the system are in position to start a cycle 45 of operation. One side of the switch is connected by a conductor AH1 to the negative conductor H3. The other side of the switch is connected by a conductor AH2 to the conductor G1. Upon closing the switch, therefore, the relay 85 will be 50 shunted and its deenergization effected. The shunting of the relay 85 is as follows: the negative conductor H3, conductor AH1, switch 86, conductor AH2, conductor G1. Thus it will be seen that conductor G1 will be connected to the 55 negative side of the battery and both terminals of the relay 85 will be connected to the negative side of the battery and the relay thus shunted.

From the above description it will be apparent that all of the supervisory relays, upon operation, 60 effect the operation of the remote signals 69 and 70. The signal 69 on the microphone panel indicates trouble with some portion of the sound control system. The trouble signal 70 which may be a siren or any audible signal is a general trouble signal. In addition, each one of the supervisory relays operates an individual trouble light to indicate the specific circuit in which the trouble has occurred. It is to be noted that the operation of the trouble signals is dependent upon the 65 continued inoperation of relay 11. The reason for this is to prevent the simultaneous operation of trouble signals and fire signals for obviously many of the supervisory circuits will be opened upon the operation of the system in response to 70 75

the operation of either the fire control circuit D or the microphone circuit R. If there actually is any trouble in the system occurring during a fire interval, this trouble will be indicated upon the deenergization of relay 11. Signals 78 and 83 are an exception to the dependency of the trouble signals upon the continued inaction of relay 11. These trouble signals are dependent upon the continued inaction of the relay 29 as they are connected to the negative side of the battery through contacts of this relay.

On the microphone panel 49 there are illustrated visual signals 86 and 87. These visual signals 86 and 87 are for the purpose of indicating trouble in an exit light control system such as that disclosed in the copending application of William D. Lindsey, Serial No. 693,053, filed October 11, 1933, which system may be interconnected for simultaneous operation with the sound system above described. Upon the operation of either one of these signals the trouble signal 70 is also operated. The operation of the trouble signal 70 and the trouble light 87 is effected by a relay 88 and the operation of the trouble signal 70 and the light 86 is effected by a relay 89. The relay 89 is in the nature of a supervisory relay and supervises the interconnection between the panel 49 and the panel of the exit light system which interconnection is for the purpose of transmitting trouble signals to the panel 49.

The manner in which this sound control system may be interconnected with the exit light system is illustrated in Fig. 4 of the drawings. In Fig. 4 the panel 90-23 represents the control panel of an exit light control system such as that disclosed in the aforementioned copending application of William D. Lindsey, Serial No. 693,053. The panel 91-1 indicates a fire alarm control panel such as that illustrated in the copending application of William D. Lindsey, Serial No. 687,278, filed August 29, 1933, and the panel 91-2 indicates the remote signal or fire department connection of the system illustrated in this application. In a complete system including the exit light control of the aforementioned application Serial No. 693,053 and the fire connection of application Serial No. 687,278, the several panels are interconnected as illustrated in Fig. 4. The interconnection between the panels 91-1 and 91-2 are fully described in the copending application Serial No. 687,278. In the interconnection of the panels 90-23 and 91-1, the contacts 90-39 and 90-39' on the panel 90-23 are connected so that in the event of the operation of the two fire circuits illustrated in the aforementioned application Serial No. 687,278 these connectors are connected to the negative side of the battery, the connectors being individual to two different fire circuits. It will be apparent from application Serial No. 693,053, that the operation of the fire circuit shown therein also connects these connectors 90-39 and 90-39' to the negative side of the battery so that the same condition is effected through the interconnection with panel 91-1.

A connector 90-51 on the panel 90 is connected to a connector 90'-51 on the announcing panel 49 by a conductor AI1 extending between the two panels. In the complete circuit, the connector 90-51 on the panel 90-23 is connected into a trouble circuit similar to the trouble circuit T. Upon the operation of a supervisory relay in the exit light control system represented by the panel 90-23, a resistance is cut out of the circuit AI and the connector 90-51

is directly connected to the negative side of the battery. Thus the connector 90'-51 on the announcing panel 49 is connected to the negative side of the battery. This connector is connected by a conductor AI2 to one side of the relay 88. The other side of the relay 88 is connected by a conductor AI3 to one side of the relay 89, the other side of which is connected by a conductor AI4 to the conductor T8 and thus to the positive connector 61b on the panel 49. In this circuit AI, the relay 89 is a supervisory relay and the relay 88 is the operative relay which upon operation effects the operation of the trouble light 87 to indicate trouble in the exit light system or control panel 90-23. If the circuit AI is broken, the relay 89 becomes deenergized. This relay is normally energized in a manner similar to the relay 67 of the circuit T.

Upon the happening of the event of trouble in the exit light control panel and the connecting of the connector 90'-51 to the negative side of the battery, the relay 88 is operated. Upon operation the relay 88 closes two sets of normally open cooperating movable and fixed contacts 88a-88b and 88c-88d. The contact 88b is connected to one side of the trouble light 87 by a conductor AJ1. The other side of the light is connected by a conductor AJ2 to the conductor U1 and thus the conductor T8 and the positive connector 61b. The movable contact 88a which cooperates with the contact 88b is connected directly to the conductor U3 and thus to the negative connector 61a. Upon the closing of the contacts 88a and 88b, therefore, the trouble light 87 is lighted. The contact 88d of relay 88 is connected by a conductor AK to the conductor U2 and the contact 88c is connected to the conductor U3. Consequently, the closing of these two contacts completes a circuit to the trouble bell 70 which circuit includes conductor T4, conductor U1, trouble bell 70, conductor U2, conductor AK, contacts 88d and 88c of relay 88 and conductor U3. The operation of relay 88, therefore, effects the operation of the trouble light 87 and the trouble bell 70.

Relay 89 when operated effects the operation of the trouble bell 70 and the trouble light 86 which indicates trouble in the interconnection between the panel 49 and the exit light panel 90-23. The light 86 is lighted through the engagement of contacts 89a and 89b of relay 89. The contact 89b is connected to the conductor U3 and thus to the negative connector 61a. The contact 89a is connected by a conductor AL to one side of the light 86, the other side of which is connected to the conductor AJ2 and thus to the positive connector 61b. It will therefore be apparent that with this interconnection of the several panels any trouble on either the exit light panel 90-23 or the sound control panel 7 or the interconnection between these panels and the panel 49 for the purpose of transmitting trouble signals will immediately effect the operation of the trouble bell 70 on the panel 49 and a specific light indicating the location of the trouble.

In Fig. 1, a fire circuit D is illustrated which effects the operation of the fire relay 17. In the interconnection of the sound system with the exit light system and the fire alarm system represented by the panels 90-23 and 91-1, the fire circuit D is not necessary. The fire circuits used in connection with the panel 91-1 are also used to effect the operation of the relay 17. When any fire circuit of the system, which may include

several fire circuits, is actuated either manually or automatically, the contact 19a on the panel 7 is connected to the negative side of the battery. In the interconnection of the several panels this contact 19a is connected by a conductor AM to a contact 91-19a on the panel 91-1. Upon the operation of either fire circuit as disclosed in the system of the application Serial No. 687,278, the contact 91-19a would be directly connected to the negative side of the battery. This is the effect of the operation of the fire circuit D, that is, cutting out the resistance 20 and connecting the connector 19a to the negative side of the battery. Consequently, the operation of the relay 17 is effected in the interconnection upon the operation of a fire circuit.

The battery is connected through the several panels to the panel 91-1 where the battery circuit terminates. The panel 91-1 is provided with a battery supervisory circuit and thus the battery interconnection between the panels is supervised as well as the battery.

Where a system of this type is utilized, it is frequently desirable to utilize the battery 6 for the purpose of supplying emergency power for operating some other instrumentalities, for example, electrical time clocks or a radio which might be connected into the sound system and operated through the loudspeakers 4a, 4b and 4c. When it is desired that the battery be so used there is provided an additional pair of panels 92 and 93. These panels are provided for the purpose of taking care of emergency loads. The panel 93 is provided with connectors 93a, 93b, 93c, 93d, 93e, 93f, 93g and 93h. The connector 93a is connected to the contact 93d through fixed and movable contacts 94c and 94d of a relay 94. The connectors 93b and 93c are connected through fixed and movable contacts 94a and 94b of relay 94. Connector 93e is connected to connector 93d through fixed and movable contacts 94e and 94f of relay 94, and connectors 93f and 93g are connected through fixed and movable contacts 94g and 94h of relay 94. The connectors 93a and 93b receive power from the battery to which they are connected through the panel 92. Power is taken from the panel to supply, for example, program clocks, through the contacts 93c and 93d. The supply of power is therefore dependent upon the continued inoperation of relay 94. When a radio is used in conjunction with the sound system, it is connected into the system through the connectors 93e and 93f on the panel 93. The output of the radio is connected to these two connectors and the connectors 93g and 93h are connected into the sound system of Fig. 1. Thus, upon operation of the relay 94 the connection between the radio and the sound system is broken. Likewise, the connection between the contactors 93a, 93b and 93c and 93d is broken upon the operation of relay 94 so that no current is supplied, or can be supplied to the program clocks while this relay is operated. The relay 94 is operated upon the operation of a fire relay such as the relay 17 so that when the system operates in response to a fire, no current is supplied to the program clocks and the radio is disconnected from the system. All of the current from the battery is thus available for the operation of the fire signal system.

Panel 92 contains the control elements for two trickle chargers for the thirty-two volt battery. This panel contains a pair of contactors 92a and 92b which are respectively connected to the positive and negative sides of the thirty-two volt

battery and a pair of contactors 92c and 92d which are respectively connected to the positive and negative side of a six volt battery supplying the system with current at six volts such as the battery 91-4. The connectors 92a and 92b are directly connected to connectors 92e and 92f which are connected to the connectors 6a and 6b on the panel 7 and the connectors 92e and 92d are directly connected to connectors 92g and 92h which are connected to the battery connectors of panel 91-2. The panel 92 also carries relays 95, 96, 97 and 98, the trickle chargers 99 and 100 for the thirty-two volt battery, a trickle charger 101 for the six volt battery and connectors 92i and 92j which are connected to the connectors 93a and 93b of the panel 93 through conductors AN1 and AN2. Connectors 92k and 92l on the panel 92 are connected to a source of alternating current such as that usually supplied to a building. These connectors are connected directly to movable contacts 98b and 98e of the relay 98 by conductors AO1 and AO2. The primary of the charger 101 is connected across the conductors AO1 and AO2 by conductors AP1 and AP2. The secondary of the trickle charger 99 is connected across the conductors AQ1 and AQ2 which connect the connectors 92e and 92d with the connectors 92g and 92h respectively. The charger is connected across these conductors by conductors AP3 and AP4. Thus the trickle charger supplies a steady current to the six volt battery.

Normally, the contacts 98b and 98e of relay 98 are in engagement with fixed cooperating contacts 98a and 98d. These latter contacts are connected respectively through conductors AO3 and AO4 to the primary of the charger 99. This charger provides a charging current of 1.5 amperes for the thirty-two volt battery. The secondary of the charger is connected by conductors AO5 and AO6 respectively to stationary contacts 98i and 98j of relay 98. These fixed contacts 98i and 98j are respectively connected through movable contacts 98h and 98k of relay 98 to conductors AO7 and AO8 which are also connected to conductors AO9 and AO10 which connect the connectors 92a and 92b to the connectors 92e and 92f. Thus normally the primary of the charger 99 is connected to the source of alternating current and the secondary of the charger is connected to the thirty-two volt battery.

The connectors 92c and 92j of the panel 92 through which the emergency power is supplied to the program clocks, are connected across the conductors AO9 and AO10 in series with the relay 95. One side of the relay 95 is connected by a conductor AR1 to the positive conductor AO9 and the other side of the relay 95 is connected by a conductor AR2 to the connector 92j. The relay 95 has a pair of fixed and movable contacts 95a and 95b which are normally open but which upon operation of the relay 95 are closed. The contact 95b is connected through a conductor AS1 and a resistance 102 to a stationary contact 98n of the relay 98. The stationary contact 98n is normally engaged by a movable contact 98m which is connected by a conductor AS2 to the conductor AO8 and thus to the negative conductor AO10. The fixed contact 95a of the relay 95 is connected through a conductor AS3 to one side of the relay 96. The other side of the relay 96 is connected through a conductor AS4 to the positive conductor AO9. Upon operation of relay 95, therefore, by the increased current due to an emergency supply of power the relay 96 is energized, the circuit being completed through the contacts 95a

and 95b of relay 95. The relay 96 has two pair of movable and fixed cooperating contacts 96a—96b and 96c—96d. The contact 96d is connected to the conductor AS4. Its cooperating contact 96c which is normally disconnected therefrom is connected through a conductor AT1 to one side of the relay 97. The other side of the relay 97 is connected through a conductor AT2 to the negative conductor AO10. Thus upon energization of the relay 96 the relay 97 is connected across the positive and negative conductors AO9 and AO10. This relay 97 is of such a winding and construction that it is not actuated except on a battery which has an output of 2.3 volts per cell. Thus if the voltage per cell is below this rating, the relay 97 is not operated. The relay 97 has a pair of fixed and movable contacts 97a and 97b which are connected in series with the contacts 96a and 96b of the relay 96. Contact 96a of relay 96 is connected to conductor AS3. Contact 96b is connected through conductor AS1 to contact 97b of relay 97. Contact 97a of relay 97 is connected through a conductor AU2 to one side of the relay 98. The other side of the relay 98 is connected to the conductor AO8 and thus to the negative conductor AO10. Upon the operation of the relay 96, therefore, and the continued inoperation of relay 97, relay 98 is operated, the circuit therefor being as follows: negative conductor AO10, conductor AO8, conductor AS2, contacts 98m and 98n of relay 98, resistance 100, conductor AS1, contacts 95b and 95a of relay 95, conductor AS3, contacts 96a and 96b of relay 96, conductor AU1, contacts 97b and 97a of relay 97, conductor AU2, relay 98, conductor AO7 and positive conductor AO9. Upon operation, relay 98 moves the movable contacts 98b and 98e out of engagement with contacts 98a and 98d and into engagement with contacts 98c and 98f. Also movable contacts 98h, 98k and 98m are respectively disconnected from fixed contacts 98i, 98l and 98n, and contacts 98h and 98k are respectively connected to contacts 98a and 98j.

The operation of relay 98 disconnects the battery from the charger 99 and connects it to the charger 100 which supplies a current of six amperes at thirty-two volts. The primary of charger 100 is connected through conductors AV1 and AV2 to stationary contacts 98c and 98f of the relay 98. Thus upon the operation of the relay the primary of the charger is connected across the alternating current circuit. The secondary of the charger 100 is connected through conductors AV3 and AV4 to fixed contacts 98g and 98j of relay 98. When the relay operates and contacts 98h and 98k are connected to the contacts 98g and 98j the secondary of the charger is connected to the conductors AO7 and AO8 and thus to the battery. A current of six amperes is therefore supplied to the battery when an emergency load is added to the battery. This emergency load is of course cut out in the event of a fire but the added current supplied to the battery serves to maintain the battery in proper condition to take care of a fire signal if one should come through.

When the battery voltage of the thirty-two volt battery 6 is increased to 2.3 volts per cell, the relay 97 will operate. Upon operating the contacts 97a and 97b are disconnected, breaking the circuit to the relay 98 and effecting the de-energization of the relay. Upon the happening of such an event the conditions are brought back to those originally described. The relay 97 can

not come in to the circuit without the presence of an emergency load but its period of service may extend beyond the period of the emergency load. Such relays as this are well known in the art.

This same system may be used in theatres, hospitals and asylums. In hospitals and asylums the loudspeakers are not placed in the rooms of the inmates but only where they will be heard by the attendants. In such case, a special musical record represents a confidential signal known to the attendants. Where a confidential signal is desirable, the speakers may be grouped in zones so that only the affected zone will know of the danger.

Obviously, features of the systems disclosed in the copending applications of William D. Lindsey, Serial No. 686,913, filed August 26, 1933, and Serial No. 693,056, may be used in conjunction with the complete interconnected system. The interconnection of the features disclosed in these applications will be readily apparent from the above description.

It will be obvious that various changes may be made by those skilled in the art in the details of the signal system disclosed in the drawings and described immediately above as well as in the interconnected system disclosed and described within the principle and scope of the invention as expressed in the appended claims.

I claim:

1. In a signal system, a sound reproducing system, a central station for controlling the operation of the sound reproducing system including means for operating the sound system as an address system, additional means for effecting the operation of the sound system to give audible directions including a record and means for delivering the recorded sound into the sound reproducing system, and means adapted to be operated upon the existence of a particular condition for effecting the operation of said additional means to effect the operation of the sound system.

2. In a signal system, a sound reproducing system, a central station for controlling the operation of the sound reproducing system including means for operating the sound system as an address system, additional means for effecting the operation of the sound system to give audible directions including a record and means for delivering the recorded sound into the sound reproducing system, means adapted to be operated upon the existence of a particular condition for effecting the operation of said additional means for effecting the operation of the sound system, and means for cutting out said first mentioned means for effecting the operation of the sound system upon the operation of said additional means.

3. In a signal system, a sound reproducing system, means for operating the sound reproducing system as a public address system, means for effecting the operation of the sound system mechanically to give audible directions, control means for said mechanical operating means, and time control means operative upon the operation of said control means for rendering the system inoperative as a public address system for a predetermined time interval.

4. In a signal system, an electrical sound reproducing system including a plurality of loud speakers, an amplifier and a central station for controlling the operation of the sound reproducing system including means for effecting the operation of the sound reproducing system for

5 directing a course of procedure including a sound record, an electrical pick-up cooperating with the sound record and connected to the amplifier, means for operating the sound record, and control means for said record operating means adapted to be actuated upon the existence of a particular condition.

5. In a signal system, an electrical sound reproducing system including a plurality of loud speakers, an amplifier and a central station for controlling the operation of the sound reproducing system including means for effecting the operation of the sound reproducing system for directing a course of procedure including a sound record, an electrical pick-up cooperating with the sound record and connected to the amplifier, means for operating the sound record, and thermostatic control means for said record operating means adapted to effect the operation thereof upon the existence of abnormal thermal conditions.

6. In a signal system, an electrical sound reproducing system including a plurality of loud speakers, an amplifier and a central station for controlling the operation of the sound reproducing system including means for effecting the operation of the sound reproducing system for directing a course of procedure including a sound record, an electrical pick-up cooperating with the sound record and connected to the amplifier, means for operating the sound record, and thermostatically and manually operated control means each adapted to effect the operation of the sound record.

35 7. In a signal system, an electrical sound reproducing system including a plurality of loud speakers, an amplifier and a central station for controlling the operation of the sound reproducing system including means for effecting the operation of the sound reproducing system for directing a course of procedure including a sound record, an electrical pick-up cooperating with the sound record and connected to the amplifier, means for operating the sound record, control means for said record operating means, means for effecting the operation of the sound reproducing means as a public address system including a microphone and means for operatively connecting the microphone to the amplifier, and means for rendering said microphone connecting means inoperative upon the operation of the sound record operating control means.

8. In a signal system, an electrical sound reproducing system including a plurality of loud speakers, an amplifier and means for effecting the operation of the sound reproducing system for directing a course of procedure including a sound record, an electrical pick-up cooperating with the sound record and connected to the amplifier, means for operating the sound record, control means for said record operating means, means for effecting the operation of the sound reproducing means as a public address system including a microphone and means for operatively connecting the microphone to the amplifier, and time controlled means operative for rendering said microphone connecting means inoperative for a definite time interval upon the operation of the sound record operating control means.

70 9. In a signal system of the type described, a sound reproducing system, a central station for

controlling the operation of the sound reproducing system including means for effecting the operation of the system as an address system, additional means for effecting the operation of the sound system to give audible directions including a record and means for delivering the recorded sound into the sound reproducing system, means for effecting the operation of said additional means upon the existence in the building of a particular condition, and means operative 10 conjointly with the operation of said last mentioned means for rendering the system inoperative as an address system.

10. In a signal system of the type described, a sound reproducing system, means for effecting 15 the operation of the system as an address system, additional means for effecting the operation of the system to give audible directions including a record and means for delivering the recorded sound into the sound reproducing system, means for effecting the operation of said additional means upon the existence in the building of a particular condition, and time control means operative upon the operation of said last mentioned means to render the system inoperative as a public 25 address system.

11. In a signal system of the type described, a sound reproducing system, a central station for controlling the operation of the sound reproducing system including means for effecting the 30 operation of the system as an address system, additional means for effecting the operation of the system to give audible directions including a record and means for delivering the recorded sound into the sound reproducing system, a series of 35 electrically actuated local signals, a remote signal, and means for effecting the simultaneous operation of said additional means and the local and remote signals upon the existence of a particular condition in the building.

12. In a signal system of the type described, a sound reproducing system, means for effecting the operation of the system as an address system, additional means for effecting the operation of the system to give audible directions including a record and means for delivering the recorded sound into the sound reproducing system, a series of electrically actuated local signals, a remote signal, means for effecting the simultaneous operation of said additional means and the local 50 and remote signals upon the existence of a particular condition, and means operative upon the operation of said last mentioned means for rendering the sound reproducing system inoperative as an address system.

13. In a signal system of the type described, a sound reproducing system, a central station for controlling the operation of the sound reproducing system including means for effecting the operation of the system as an address system, additional means for effecting the operation of the system to give audible directions including a record and means for delivering the recorded sound into the sound reproducing system, means for effecting the operation of said additional means including a thermostat, and means operative upon the operation of said last mentioned means to render the system inoperative as an address system.
